MEANS AND METHOD FOR USE IN LASTING SHOES

Fred N. La Chapelle, Beverly, Mass., assignor to
United Shoe Machinery Corporation, Paterson,
N. J., a corporation of New Jersey

Application December 14, 1932, Serial No. 647,226

46 Claims. (Cl. 12—107)

This invention relates to means and methods for use in lasting shoes, and more particularly to means and methods having in view the holding of the upper in lasted position until conditions are such that it need no longer be held extraneously by reason, for example, of the setting of cement used to secure it in lasted position. The invention is herein illustrated in its application to the lasting of the toe ends of shoes, but it is to be understood that it is likewise applicable to the lasting of other portions, for example, the heel ends.

In one aspect, the invention provides novel means adapted to be carried by end-lasting wipers inwardly over the bottom of a shoe and then to be fastened to the shoe to hold the upper in lasted position. In each of two alternative forms of construction herein disclosed this means comprises an upper-holding device having members formed for attachment to the wipers prior to the lasting operation for wiping the upper inwardly over the shoe bottom by the movement of the wipers, the members being attachable to the shoe while the wipers are over the shoe bottom. As illustrated, these members are mounted in recesses provided in the wiping faces of the wipers, and in one form disclosed they extend over the wiping edges of the wipers and are pressed against these edges by a spring that connects them together, while in the other form they are so applied to the wipers that they are spaced from the wiping edges. The members, as further herein illustrative, are fastened to the shoe by fastenings inserted through openings provided in the wipers and driven into the shoe and last to clamp the members down upon the shoe bottom. Novel features of the invention are to be recognized in the construction of the upper-holding means, in the combination of such means with wipers specially constructed to apply the same to the shoe, and in details of the wiper construction for the purposes in view.

In a further aspect the invention provides a novel method whereby means operated by end-embracing wipers to wipe the marginal portion of an upper initially inward over a sole on a last so that said marginal portion lies, for example, throughout its width in generally parallel relation to the bottom of the last, is thereafter fastened to the shoe to hold the upper in lasted position and is removed from the lasting machine with the shoe.

The novel features of the invention and the novel method will now be more particularly de-

scribed by reference to the accompanying drawings and pointed out in the claims.

In the drawings,

Fig. 1 is a plan view of a portion of a bed-lasting machine having wipers constructed in accordance with this invention for applying to the toe end of a shoe one form of upper-holding means provided by the invention and shown in position on the shoe adjacent to the wipers;

Fig. 2 shows one of the wipers in elevation with the corresponding upper-holding member applied thereto;

Fig. 3 is a section through a wiper and the upper-holding member;

Fig. 4 is a section on the line IV—IV of Fig. 1, illustrating more clearly the relation of an upper-holding member to the corresponding wiper and the relation of these parts to the shoe at the end of the lasting operation;

Fig. 5 is a plan view of the forepart of a shoe with the toe portion of the upper held in lasted position by the form of upper-holding means shown in the previously mentioned figures;

Fig. 6 is a plan view of a portion of a bed-lasting machine having toe wipers constructed to apply to a shoe an alternative form of upper-holding means provided by the invention, illustrating how such means is applied;

Fig. 7 is a perspective view of the wipers shown in Fig. 6 as viewed from below; and

Fig. 8 is a perspective view of the forepart of a shoe with the alternative form of upper-holding means fastened thereto.

While the invention is not limited to the use of any particular type of lasting machine, it is herein illustrated by reference to a bed-lasting machine of the well-known type disclosed in Letters Patent No. 1,018,477, granted on February 27, 1912 upon an application of Matthias Brock. It will be understood that in such a machine the shoe is supported at the heel end and the forepart for the lasting operation by means not herein shown. For lasting the toe portion of the shoe the machine is provided with toe-embracing wipers 10 carried by wiper holders 12 to which advancing movements lengthwise of the shoe and swinging or closing movements laterally of the shoe are imparted by a hand lever 14 connected to the holders by a plunger 16 and links 18, the

holders being guided in the proper paths by cam slots 20 and 22 formed therein and cooperating with rolls (not shown) connected to a cover plate 45

40

55

24. It will be further understood that in machines of the illustrated type the wipers and their

operating means are supported by a carrier movable upwardly and downwardly under control of a treadle (not shown) for wiping the upper first heightwise of the toe by means of the wipers and for pressing its marginal portion downwardly upon the insole during and after the movements of the wipers to wipe the upper inwardly over the insole. The invention is herein illustrated by reference to the lasting of a shoe of that type 5 in which the marginal portion of the upper is lasted over the outer face of the insole in generally parallel relation to the last bottom, the shoe herein shown being specifically a shoe of the Littleway type, and the illustrated machine 10 is further provided with a toe band 25 such as frequently used for embracing and clamping the upper around the toe end of the last in operating on shoes of that kind, together with toe-band-operating mechanism of the same general character 15 as disclosed in Letters Patent No. 1,495,169, granted on May 27, 1924 upon an application of J. Fausse and R. E. Duplessis.

For applying to the shoe the form of upper-holding device shown in Figs. 1 to 5, inclusive, the wipers 10 are provided in their wiping faces, i. e., in the faces thereof that are opposite the bottom face of the last when the wipers are over the shoe bottom, with recesses 26 of less depth than the thickness of the wipers to receive plane portions 28 of upper-holding members or plates 30 which may be formed of sheet metal or other suitable material and are applied to the wipers in fixed relation thereto prior to the lasting of the toe, the recesses 26 being of such depth that the lower faces of the portions 28 are in the same plane as the portions of the wiping faces of the wipers beyond the recesses. The members 30 have also portions 31 curved to extend transversely of the plane of the wipers and outwardly in such manner as to embrace the forward edges of the wipers, which are commonly and herein termed the wiping edges, although in the construction shown the portions of these edges along which the members 30 extend are not in actual contact with the upper; and the members are also curved lengthwise of the wiping edges to conform substantially to the contour of these edges and to the edge contour of the end of the shoe bottom. It will accordingly be evident that the wipers serve to support the members 30 when the latter are applied thereto; and to assist in maintaining the members in proper relation to the wipers and to each other there is provided a loop spring 32 which connects the members together at their forward ends and tends to spread them apart so as to hold them in place on the wipers, the ends of the spring 32 being inserted in openings provided in upstanding lugs 34 on the members. It will be understood that as the wipers are closed inwardly over the shoe bottom the members 30 are swung inwardly toward each other against the resistance of the spring 32. Further to assist in supporting and holding the members in place on the wipers, they 60 are provided with spring clips 36 which extend over the top faces of the wipers and snap into recesses 38 (Fig. 4) in these faces.

From the foregoing description it will be evident that as the wipers are advanced and closed 70 to wipe the marginal portion of the upper inwardly over the insole the portions 28 of the members 30 are in wiping contact with the upper between the wipers and the bottom of the last. At the end of the wiping operation the members 75 30 are fastened to the shoe to hold the upper in

lasted position. While they may be fastened in various ways, there is herein illustrated the use of tacks *t* for this purpose, the tacks being driven into the shoe bottom in directions substantially perpendicular to the shoe bottom through openings 40 provided in the plane portions 28 in such manner as to clamp the members down upon the shoe bottom by the tack heads. To permit the passage of the tacks the wipers 10 are provided at their wiping edges with openings 42 extending through them from the recesses 26 in directions perpendicular to the plane of the wipers, in which there may be inserted, for example, the nozzle of a hand tacker. After the upper-holding members have thus been fastened to the shoe 10 the wipers are withdrawn from the shoe by retracting them from over the shoe bottom, the spring clips 36 slipping out of the recesses 38 as the wipers are retracted.

In the construction shown in Figs. 6 and 7 the 20 wipers 44 are provided in their wiping faces with curved recesses 46 of less depth than the thickness of the wipers and terminating laterally short of the wiping edges of the wipers instead of extending to these edges as in the construction 25 previously described, and formed to enter these recesses are correspondingly curved upper-holding members or plates 48 and 50 (Fig. 8) of a contour approximately like that of the edge of the end portion of the shoe bottom, the construction 30 being such that when these members are in place in the recesses 46 their lower faces are flush with the portions of the wiping faces of the wipers that are beyond the recesses. The upper-holding members are thus in wiping contact with 35 the upper between the wipers and the bottom of the last in fixed relation to the wipers as the wipers are moved inwardly over the shoe bottom. Projecting from the members 48 and 50 are studs 52 and 54 arranged to enter recesses or openings 40 56 and 60 extending through the wipers from the recesses 46 to assist in positioning and holding the members in proper relation to the wipers. The members 48 and 50 are provided with openings 55 to receive tacks *t* driven into the shoe bottom in directions substantially perpendicular to the shoe bottom to fasten the members to the shoe and to clamp them down upon the shoe bottom by the tack heads; and to permit the driving of the tacks the wipers are provided with 60 openings 62 extending through them from the recesses 46 in directions perpendicular to the plane of the wipers, through which the tacks may be inserted, for example, by use of a hand tacker presented with its nozzle in the openings 65 62. The member 48 is further provided with an offset portion 64 arranged to overlap the member 50 in sliding contact therewith as the wipers are closed inwardly over the shoe bottom, and in this overlapping portion there is provided an opening 60 to receive a tack *t'* which may be inserted in the V-shaped space between the wipers when the latter are in their closed positions, as illustrated in Fig. 6. In the forward end of the member 50 is a notch 66 (Fig. 8) to receive the shank of the 65 tack. The tack *t'* thus serves to clamp both members down at the extreme end of the shoe bottom. To provide room for the offset portion 64 the wipers are provided with recesses 68 which are deeper than the recesses 46. It will be 70 understood that after the tacks have been driven the wipers are first moved upwardly away from the shoe bottom to detach them from the studs 52 and 54, after which they are retracted from over the shoe bottom. In the construction shown 75

the members 48 and 50 and their studs 52 and 54 are so formed as to fit closely within the corresponding recesses and openings in the wipers, so that after the members have been placed in the wipers they will be frictionally held from falling until the wipers are moved to carry them inwardly over the shoe bottom. There may, however, be provided any suitable means to assist in holding the members in place.

10 The character of the lasting operations performed before the upper-holding members are fastened to the shoe in the manner described may vary in accordance with the preferences of different manufacturers. In lasting toes with cement it is a common practice to wipe the upper materials, including the upper leather, the box toe stiffener and the lining, heightwise of the toe by the use of the wipers and then to wipe the marginal portions of these materials inwardly over the insole around the toe prior to the application of any upper-holding cement to the shoe, after which the operator retracts the wipers and trims the margin of the toe stiffener and the lining back approximately to the edge of the insole around the toe. After the trimming operation the operator applies cement to the marginal portion of the upper leather and then wipes the latter again inwardly over the insole by advancing and closing the wipers. By use of the treadle provided for that purpose he also operates the wipers to press the upper firmly down upon the outer face of the insole. Either form of upper-holding means disclosed will preferably be applied to the wipers prior to the beginning of the toe-lasting operation to serve in part as means for wiping the upper inwardly over the insole, and it will be evident that in the use of the construction disclosed in Figs. 1 to 5, inclusive, the members 30 serve also by contact with the upper to wipe it heightwise of the toe. In the use of either form of upper-holding means the upper-holding members are fastened to the shoe by the tacks while they are pressed firmly down upon the shoe bottom by the wipers at the end of the wiping movements of the wipers, after which the operator withdraws the wipers, leaving the members fastened to the shoe. Thereafter the shoe is removed from the machine with the upper-holding members fastened to it for holding the upper until the cement has set. After the setting of the cement the members are removed from the shoe by prying them upwardly from the shoe bottom, thus withdrawing the tacks from the shoe. It will be evident that by use of the means disclosed insurance is afforded against any loss of the lasting tension and against displacement of any portion of the upper around the toe from the position that it assumes under the action of the wipers in the lasting operation, and that the pressure of the upper-holding members on the upper insures firm adhesion of the latter to the insole over a wide area.

While the invention has been described with particular reference to the lasting of the upper with cement, it is to be understood that the invention is not thus limited, but that upper-holding means of the character disclosed may be used, for example, to hold an upper in lasted position during the hardening of box-toe-stiffening material, which, after hardening, serves to maintain the toe portion of the upper in lasted position. It is further to be understood that while the invention is illustrated by reference to the manufacture of a shoe in which the marginal portion of the upper is lasted over the insole in generally

parallel relation to the bottom of the last, it is not limited to the manufacture of shoes of that particular type. As previously suggested, moreover, the invention is not limited to the lasting of the toe ends of shoes but is applicable, for example, to the lasting of the heel ends.

Having described the invention, what I claim as new and desire to secure by Letters Patent of the United States is:

1. Means for use in lasting shoes, comprising a device formed for attachment to end-lasting wipers prior to movement of the wipers inwardly over the bottom of a shoe on a last and having a portion thereof arranged to lie between the wipers and the bottom of the last for wiping engagement with the upper as the wipers are moved inwardly and another portion arranged to extend over the top of the wipers to support the device on the wipers, said device being further formed for attachment to the shoe by fastening means penetrating the shoe bottom for holding the upper in lasted position when the wipers are withdrawn from the shoe.

2. Means for use in lasting shoes, comprising a device so formed as to adapt it to be applied to end-lasting wipers and to be retained in place on the wipers by contact of the wipers therewith prior to their movement inwardly over the bottom of a shoe on a last positioned bottom upward, said device having a substantially plane portion arranged to lie between the wipers and the bottom of the last for wiping the upper inwardly and pressing it down upon the shoe bottom by movements of the wipers and having in said plane portion openings arranged to receive fastenings driven into the shoe in locations nearer the edge of the shoe bottom than the wiping edges of the wipers to fasten the device to the shoe for holding the upper in lasted position.

3. Means for use in lasting shoes, comprising a device so formed as to adapt it to be applied to end-lasting wipers prior to movement of the wipers inwardly over the bottom of a shoe on a last and provided with means arranged to extend into recesses in the wipers to assist in holding the device against displacement relatively to the wipers, a portion of said device being arranged to lie between the wipers and the bottom of the last in engagement with the overwiped upper when the wipers are over the shoe bottom and having openings therein to receive fastenings driven into the shoe bottom to fasten the device to the shoe for holding the upper in lasted position.

4. Means for use in lasting shoes, comprising members so formed as to adapt them to be applied to and supported by end-lasting wipers and to be moved by the wipers inwardly over the bottom of a shoe on a last positioned bottom upward with portions, at least, thereof in positions to wipe the upper inwardly and press it toward the bottom face of the last around the end of the shoe bottom through movements of the wipers, said members being attachable to the shoe for holding the upper in lasted position when the wipers are withdrawn from over the shoe bottom.

5. Means for use in lasting shoes, comprising members so formed as to adapt them to be applied to and supported by end-lasting wipers and to be moved by the wipers inwardly over the bottom of a shoe on a last positioned bottom upward and having substantially plane portions arranged to lie between the wipers and the bottom of the last in engagement with the overwiped upper.

- around the end of the shoe bottom when the wipers are over the shoe bottom, said members having openings therein to receive fastenings driven into the shoe bottom to fasten them to the shoe for holding the upper in lasted position.
6. Means for use in lasting shoes, comprising members so formed as to adapt them to be attached to end-lasting wipers and to be supported by contact of the wipers therewith prior to movement of the wipers inwardly over the bottom of a shoe on a last, said members having portions, at least, thereof arranged to lie between the wipers and the bottom face of the last for wiping the upper inwardly by movements of the wipers and provided with openings to receive fastenings driven into the shoe in locations nearer the edge of the shoe bottom than the wiping edges of the wipers to fasten the members to the shoe for holding the upper in lasted position.
- 10 7. Means for use in lasting shoes, comprising members so formed as to adapt them to be applied to end-lasting wipers and supported by the wipers prior to movement of the latter inwardly over the bottom of a shoe so as to be carried inwardly by the wipers, said members being attachable to the shoe by fastenings driven into the shoe bottom to fasten them in upper-holding positions.
- 15 8. Means for use in lasting shoes, comprising a device formed to enter recesses provided in the wiping faces of end-lasting wipers opposite the bottom face of a last in position to act by movement of the wipers to wipe an upper inwardly over a sole on the last and to press it down on the sole, said device having a normal contour approximately like the edge contour of the end portion of the shoe bottom and being attachable to the shoe for holding the upper in lasted position when the wipers are withdrawn from over the shoe bottom.
- 20 9. Means for use in lasting shoes, comprising a device so formed as to adapt it to be applied to end-lasting wipers prior to movement of the wipers inwardly over the bottom of a shoe with a portion, at least, thereof lying in recesses provided in the wiping faces of the wipers in position to wipe the upper inwardly over the shoe bottom around the end of the shoe by movement of the wipers, said device having openings therein to receive fastenings driven into the shoe bottom
- 25 50 to fasten it to the shoe for holding the upper in lasted position.
10. Means for use in lasting shoes, comprising a device so formed as to adapt it to be applied to end-lasting wipers and to be retained in place on the wipers prior to their movement inwardly over the bottom of a shoe on a last, a portion, at least, of said device being arranged to lie in recesses in the wiping faces of the wipers prior to their inward movement for engaging the upper between the wipers and the bottom of the last around the end of the shoe bottom and being attachable to the shoe by fastenings driven into the shoe bottom to fasten the device in upper-holding position.

- the wiping faces of end-lasting wipers to be carried by the wipers inwardly over the bottom of a shoe and attachable to the shoe for holding the upper in lasted position, said members having portions arranged to extend heightwise of the shoe over the wiping edges of the wipers and also to extend outwardly over the wipers. 5
20. Means for use in lasting shoes, comprising members each curved to extend along one side portion of an end of the bottom of a shoe and having openings therein to receive fastenings driven into the shoe bottom to fasten them to the shoe for holding the upper in lasted position, said members having substantially plane upper-engaging portions and having other portions curved to extend from said plane portions heightwise of the shoe and outwardly toward the edge of the shoe bottom. 10
21. Means for use in lasting shoes, comprising members so formed as to adapt them to be applied to end-lasting wipers for wiping an upper inwardly over a sole on a last by movements of the wipers and for then holding the upper in lasted position, and spring means tending to move said members relatively to each other in such directions as to maintain them in place on the wipers. 15
22. Means for use in lasting shoes, comprising members so formed as to adapt them to be applied to end-lasting wipers to be carried inwardly over the bottom of a shoe by the wipers, said members being attachable to the shoe for holding the upper in lasted position, and spring means tending to move said members apart laterally of the shoe to maintain them in place on the wipers. 20
23. Means for use in lasting shoes, comprising members so formed as to adapt them to be applied to end-lasting wipers to be carried by the wipers inwardly over the bottom of a shoe for holding the upper in lasted position, portions of said members being arranged to engage the edges of the wipers, and spring means tending to move said members relatively to each other in such directions as to hold them against the edges of the wipers. 25
24. Means for use in lasting shoes, comprising members each curved to extend along one side portion of an end of the bottom of a shoe and having openings therein to receive fastenings driven into the shoe bottom to fasten them to the shoe for holding the upper in lasted position, and spring means tending to spread said members apart and against the resistance of which they are movable toward each other into upper-holding positions. 30
25. Means for use in lasting shoes, comprising members each curved to extend along one side portion of an end of the bottom of a shoe and attachable to the shoe for holding the upper in lasted position, and a loop spring connecting said members together and against the resistance of which they may be swung toward each other to position them in proper relation to the shoe. 35
26. Means for use in lasting shoes, comprising a device formed to enter recesses provided in the wiping faces of end-lasting wipers in locations spaced from the wiping edges of the wipers, said device being attachable to the shoe for holding the upper in lasted position after it has been carried inwardly over the shoe bottom by the wipers. 40
27. Means for use in lasting shoes, comprising members formed to enter recesses provided in the wiping faces of end-lasting wipers in locations spaced from the wiping edges of the wipers, said members having openings therein to receive fastenings driven into the shoe bottom through openings in the wipers to fasten them to the shoe for holding the upper in lasted position. 45
28. Means for use in lasting shoes, comprising members formed to enter recesses provided in the wiping faces of end-lasting wipers to be carried inwardly over the shoe bottom by the wipers, said members being attachable to the shoe for holding the upper in lasted position and having thereon projections arranged to enter openings in the wipers and to slip out of said openings upon movement of the wipers heightwise of the shoe after the members have been attached to the shoe. 50
29. Means for use in lasting shoes, comprising members so formed as to adapt them to be applied to end-lasting wipers in positions to wipe an upper inwardly over a sole on a last by movements of the wipers and to lie between the wipers and the bottom of the last at the end of the wiping operation, said members being attachable to the shoe for holding the upper in lasted position and having thereon projections arranged to enter openings in the wipers and to slip out of said openings upon movement of the wipers heightwise of the shoe after the members have been attached to the shoe. 55
30. Means for use in lasting shoes, comprising plates curved to extend around an end of the bottom of a shoe and formed to enter recesses provided in the wiping faces of end-lasting wipers to be carried inwardly over the shoe bottom by the wipers, said plates having openings therein to receive fastenings driven through openings in the wipers to fasten the plates to the shoe for holding the upper in lasted position and one of the plates having a portion arranged to overlap the other plate at the extreme end of the shoe bottom with an opening therein to receive a fastening inserted in the space between the wipers when the wipers are closed over the shoe bottom. 60
31. Means for use in lasting shoes, comprising end-lasting wipers for wiping the marginal portion of an upper inwardly over a sole on a last around an end of the shoe bottom, said wipers having in the faces thereof that are opposite the bottom face of the last recesses of less depth than the thickness of the wipers to receive means to be attached to the shoe for holding the upper in lasted position when the wipers are withdrawn from the shoe and having openings leading from said recesses to receive fastenings driven in directions substantially perpendicular to the shoe bottom to fasten said holding means to the shoe. 65
32. Means for use in lasting shoes, comprising end-lasting wipers for wiping the marginal portion of an upper inwardly over a sole on a last around an end of the shoe bottom, said wipers having in the faces thereof that are opposite the bottom face of the last recesses of less depth than the thickness of the wipers to receive means to be attached to the shoe for holding the upper in lasted position and having openings leading from said recesses to receive fastenings driven in directions substantially perpendicular to the shoe bottom to fasten said holding means to the shoe, said recesses extending along the wiping edges of the wipers and extending also to said edges. 70
33. Means for use in lasting shoes, comprising end-lasting wipers for wiping the marginal portion of an upper inwardly over a sole on a last around an end of the shoe bottom, said wipers

- having in the faces thereof that are opposite the bottom face of the last curved recesses of less depth than the thickness of the wipers to receive means to be attached to the shoe for holding the upper in lasted position, said recesses extending lengthwise along the wiping edges of the wipers and terminating laterally short of said edges.
34. Means for use in lasting shoes, comprising end-lasting wipers for wiping the marginal portion of an upper inwardly over a sole on a last around an end of the shoe bottom, said wipers having in the faces thereof that are opposite the bottom face of the last recesses of less depth than the thickness of the wipers and spaced from the wiping edges of the wipers to receive means to be attached to the shoe for holding the upper in lasted position and having also openings extending through them from said recesses in positions to permit the passage of fastenings driven into the shoe bottom to fasten said upper holding means to the shoe.
35. Means for use in lasting shoes, comprising end-lasting wipers for wiping the marginal portion of an upper inwardly over a sole on a last around an end of the shoe bottom, said wipers having recesses in the faces thereof that are opposite the bottom face of the last, and a device formed to enter said recesses to be carried by the wipers inwardly over the shoe bottom in substantially fixed relation to the wipers, said device being attachable to the shoe to hold the upper in lasted position when the wipers are withdrawn from the shoe.
36. Means for use in lasting shoes, comprising end-lasting wipers for wiping the marginal portion of an upper inwardly over a sole on a last around an end of the shoe bottom, said wipers having in the faces thereof that are opposite the bottom face of the last recesses extending along their wiping edges and extending also to said edges, and a device formed to enter said recesses and also to extend over the wiping edges of the wipers to be carried by the wipers inwardly over the shoe bottom in wiping contact with the upper, said device being detachable from the wipers for holding the upper in lasted position.
37. Means for use in lasting shoes, comprising end-lasting wipers for wiping the marginal portion of an upper inwardly over a sole on a last around an end of the shoe bottom, said wipers having in the faces thereof that are opposite the bottom face of the last curved recesses extending along the wiping edges of the wipers and extending also to said edges, and curved members formed to enter said recesses and having portions arranged to extend over the wiping edges of the wipers to be engaged by the wipers to force the members inwardly over the shoe bottom, said members having openings therein to receive fastenings driven into the shoe bottom to fasten them to the shoe for holding the upper in lasted position.
38. Means for use in lasting shoes, comprising end-lasting wipers for wiping the marginal portion of an upper inwardly over a sole on a last around an end of the shoe bottom, said wipers having recesses in the faces thereof that are opposite the bottom face of the last and having openings extending through them from said recesses in directions perpendicular to the plane of the wipers, and a device formed to enter said recesses to be carried by the wipers inwardly over the shoe bottom, said device being attachable to the shoe by fastenings inserted through said openings in the wipers for holding the upper in lasted position.
39. Means for use in lasting shoes, comprising end-lasting wipers for wiping the marginal portion of an upper inwardly over a sole on a last around an end of the shoe bottom, said wipers having in the faces thereof that are opposite the bottom face of the last recesses extending lengthwise along their wiping edges and terminating laterally short of said edges, and members formed to enter said recesses to be carried by the wipers inwardly over the shoe bottom, said members being attachable to the shoe for holding the upper in lasted position when the wipers are withdrawn from the shoe.
40. Means for use in lasting shoes, comprising end-lasting wipers for wiping the marginal portion of an upper inwardly over a sole on a last around an end of the shoe bottom, said wipers having in the faces thereof that are opposite the bottom face of the last recesses extending lengthwise along their wiping edges and terminating laterally short of said edges and having also openings extending through them from said recesses, and members formed to enter said recesses to be carried by the wipers inwardly over the shoe bottom, said members having openings therein arranged to receive fastenings driven into the shoe bottom through said openings in the wipers to fasten them to the shoe for holding the upper in lasted position.
41. Means for use in lasting shoes, comprising end-lasting wipers for wiping the marginal portion of an upper inwardly over a sole on a last around an end of the shoe bottom, said wipers having in the faces thereof that are opposite the bottom face of the last recesses extending lengthwise along their wiping edges and terminating laterally short of said edges and having also openings extending from said recesses transversely of the plane of the wipers, and members formed to enter said recesses to be carried by the wipers inwardly over the shoe bottom and having thereon projections arranged to extend into said openings in the wipers, said members being attachable to the shoe by fastenings driven into the shoe bottom for holding the upper in lasted position.
42. That improvement in methods of lasting shoes which consists in wiping the marginal portion of an upper initially inward over the bottom of a last and over a sole on the last around an end of the shoe bottom so that said marginal portion lies throughout its width in generally parallel relation to the bottom of the last by the use of means operated in wiping contact with the upper by the end-embracing wipers of a lasting machine, and thereafter fastening said means to the shoe in such manner as to hold the upper pressed upon the sole toward the bottom face of the last around the end portion of the shoe bottom independently of the wipers and removing the shoe from the machine with said means fastened to it.
43. That improvement in methods of lasting shoes which consists in wiping the marginal portion of an upper initially inward over the bottom of a last and over a sole on the last around an end of the shoe bottom so that said marginal portion lies throughout its width in generally parallel relation to the bottom of the last by the use of means operated in wiping contact with the upper by the end-embracing wipers of a lasting machine, and thereafter driving fastenings into the shoe bottom to fasten said means to the shoe in such manner as to hold the upper pressed upon the sole.

the sole toward the bottom face of the last around the end portion of the shoe bottom independently of the wipers and removing the shoe from the machine with said means fastened to it.

- 5 44. That improvement in methods of lasting shoes which consists in applying to the end-embracing wipers of a lasting machine prior to the operation of said wipers on a shoe means to be operated by the wipers in wiping contact with the upper and by the use of said means and the wipers wiping the marginal portion of the upper inwardly over the bottom of the last and over a sole on the last around an end of the shoe bottom so that said marginal portion lies throughout its 10 width in generally parallel relation to the bottom of the last, and thereafter fastening said means to the shoe to hold the upper pressed upon the sole toward the bottom face of the last independently of the wipers and removing the shoe from the machine with said means fastened to it.

- 15 45. That improvement in methods of lasting shoes which consists in wiping the marginal portion of an upper initially inward over the bottom of a last and over a sole on the last around an end of the shoe bottom by the use of plates oper-

ated in wiping contact with the upper by the end-embracing wipers of a lasting machine, and thereafter fastening said plates to the shoe to hold the upper in lasted position independently of the wipers and removing the shoe from the machine with said plates fastened to it.

- 5 46. That improvement in methods of lasting shoes which consists in applying to the end-embracing wipers of a lasting machine prior to their operation on a shoe plates to be operated 10 in wiping contact with the upper by the wipers and by the use of said plates and the wipers wiping the marginal portion of the upper inwardly over the bottom of a last and over a sole on the last around an end of the shoe bottom so 15 that said marginal portion lies throughout its width in generally parallel relation to the bottom of the last, and thereafter driving fastenings into the shoe bottom to fasten said plates to the shoe in such manner as to hold the upper pressed upon the sole toward the bottom face of the last independently of the wipers and removing the shoe from the machine with the plates fastened to it.

FRED N. LA CHAPELLE.
